NUT

Charles G. Mackie, Glen Ellyn, and Phillip G. Holliday, Bellwood, Ill., assignors to Standard Screw Company, Bellwood, Ill., a corporation of New Jersey

Filed Mar. 11, 1966, Ser. No. 1,420

Term of patent 7 years

(Cl. D54—9)

FIG. 5.

FIGURE 1 is a side view of our design for a nut, FIGURE 2 is a longitudinal section taken at line 2—2 of FIGURE 1, FIGURE 3 is a top plan view, FIGURE 4 is a bottom view, and FIGURE 5 is a perspective looking in the direction of the top of the nut.

We claim:

The ornamental design for a nut, as shown.
